Patented Jan. 9, 1962

192,047

MINIATURE WASHING MACHINE

Guy F. Farmer, P.O. Box 225, Blackshear, Ga.

Filed Oct. 20, 1960, Ser. No. 62,547

Term of patent 14 years

(Cl. D49—1)

Fig. 1

Fig. 2

FIG. 1 is a top perspective view of a miniature washing machine, illustrating my new design;

FIG. 2 is a top plan view thereof; and

FIG. 3 is a perspective view thereof in open position.

The bottom not shown is substantially the same as the top shown.

I claim:

The ornamental design for a miniature washing machine as shown and described.
